UNITED STATES PATENT OFFICE

2,119,537

CONTAINER FOR AND DISPENSER OF RIBBON-LIKE MATERIAL

George H. Halpin, St. Paul, Minn., assignor to Minnesota Mining & Manufacturing Company, St. Paul, Minn., a corporation of Delaware

Application November 23, 1932, Serial No. 644,064
In Great Britain August 9, 1932

10 Claims. (Cl. 216—33)

The invention relates broadly to a device for containing and dispensing rolls of ribbon-like material, and more particularly to a device for retaining and dispensing rolls of adhesive tape of a nature such that temporary adhesion between the successive layers of the tape in the roll will normally prevent the tape from unrolling except by the act of the user.

This invention as represented by its several forms finds particular utility for holding and dispensing pressure sensitive adhesive tapes, such, for example, as those disclosed in the patent to Drew 1,760,820, May 27, 1930 and wherein by virtue of the tacky nature of the adhesive layer and the structure of the container, the tape may be dispensed directly from the container onto the surface to which it is to be applied.

The principal objects and advantages of this invention reside in the provision of a device for containing and dispensing a roll of ribbon-like material, which is simple and economical of construction, of such a nature as to readily allow the removal or insertion of a roll of the ribbon-like material, and provided with a means for severing any desired length of such material from the roll; the provision of an improved container for pressure sensitive tape having severing means forming a part of the container; the provision of an improved container of the character referred to wherein the tape roll is available from without the container so that the rotation of the roll of tape may be arrested as desired to facilitate severing; the provision of an improved container for pressure sensitive tape which is of such economical construction as to permit the container to be marketed with roll of tape so as to make convenient the use of the tape; and the provision of an improved container for pressure sensitive tape which will insure efficient and accurate dispensing of the tape and thus avoid waste.

The invention has as further objects the provision of a container for tapes by which the tape may be dispensed directly from the roll onto a surface to which it is to be applied and in which said container is provided with a severing blade whereby the tape dispensed may be conveniently severed from the roll, at the same time leaving available a part of the roll so that it is presented convenient of access for dispensing additional portions of the tape.

While the various forms of this device as shown and described are designed particularly for use for containing and dispensing rolls of pressure sensitive adhesive tape, the device may be used

with other tapes, and therefore finds a wide field of utility in connection with analogous materials.

The foregoing and such further objects and advantages as may appear or be pointed out as this description proceeds are attained in the structural embodiments illustrated in the accompanying drawings, in which:

Figure 1 is a view of the flat stamping used in certain forms of this device.

Figure 2 is a side elevation of one form of the device completely formed from the blank shown in Figure 1.

Figure 3 is an edge elevation.

Figure 4 is a view similar to Figure 2 of another form of the device with a portion cut away to show the spool of tape in position and a method of using the device.

Figures 5 and 6 are side elevation and edge views respectively of a further modified form of the device formed from a modified blank similar to that shown in Figure 1.

Figures 7 and 8 are side elevation and edge views respectively of a further form of the device, and

Figures 9 and 10 show the stampings from which the form shown in Figures 7 and 8 is made.

Referring now to the drawings and first more particularly to Figures 1 to 3 inclusive, one form of the device is made from the single sheet metal stamping 10, comprising two disc-like side portions 11 and 12 connected by a bridge portion 13 forming an abutment, which is provided with a laterally extended portion 14 having a serrated edge 15. This blank is formed over a suitable die so that the sides 11 and 12 are bent along the dotted lines 11a and 12a, respectively, so that they are held in parallel spaced relationship by the bridge portion 13. The sides 11 and 12 possess a desired degree of resiliency for a purpose which will hereinafter appear.

The annular portions of the sides 11 and 12 inside of the dotted lines 11a and 12a, respectively, are bent to form the inwardly projecting circular flanges 16 and 17 respectively which act as spindles for the roll of tape 18 which is wound on a hollow core 19, which may be conveniently a short section of cardboard tube. The portion 14 is bent along the dotted line 14a to an angular relation with the bridge portion 13 as shown, thus placing the serrated edge 15 in a convenient position for use in severing any desired length of the tape which has been removed from the roll.

After the respective parts are in their desired relation with each other the areas indicated by

the dotted lines 20a and 21a are formed into the ribs 20 and 21 respectively, which act as reinforcing means to impart a certain degree of rigidity and to hold the portions of the device in the desired relative positions.

The device made as above described provides a simple and convenient structure in which the roll 18 of adhesive material may readily be inserted or removed by springing apart the side members 11 and 12. When thus inserted it is held in place and yet is revolvable on the spindles 16 and 17, and the tape may be readily removed in any desired length by holding the device between the thumb and forefinger of one hand and pulling outwardly on the edge of the tape. The rotation of the roll on the spindles may be readily controlled by the pressure of the thumb or finger on the side walls acting as a brake on the roll itself, and the tape may be severed at any desired point by bending it up along the portion 14 and tearing off along the serrated edge 15. This will leave the short portion of the tape which extends along the portion 14 loose on the roll to serve as a tab for unrolling the next section.

A modified form of the device is shown in Figure 4. This is made from the same stamping as shown in Figure 1 and is formed in the same way as the device shown in Figures 2 and 3 with the exception that the extended portion 14 is bent in the form of an arc as shown at 14b. In Figure 4 a portion of the wall 11 is shown cut away to show a roll of pressure-sensitive tape in position. The portion 14b is so bent and curved with relation to the side walls 11 and 12 that when these are moved along, or slightly raised from a surface, S, on which it is desired to apply the tape, the bent portion 14b may be used as an applicator to press the tape directly in place, as it is dispensed from the roll, and the tape may be severed at any desired point by tipping up the holder to bring the serrated edge 15 in contact with the tape. In Figure 4 the cut away portion shows the roll of tape in position and the way in which it is applied to the surface, S. It is obvious that the form of the device as shown in Figure 4 can also be used in the manner described above for the form shown in Figures 2 and 3, and also that to a limited extent the portion 14 of the form shown in Figures 2 and 3 may serve as an applicator similar to portion 14b of the form shown in Figure 4.

A further modified form of the device is shown in Figures 5 and 6 where the portion 14 of the blank shown in Figure 1 is dispensed with and the serrated cutting edge 15b is formed on the side of the bridge member 13 along the line 14a. In this form also, additional material is provided on the sides 11 and 12 to allow the forming of rolled circumferential beads around the outer circumference of these side members as shown at 11b and 12b.

This form of the device is used in the same manner as described above for the form shown in Figures 2 and 3.

It is readily seen that the rolled edges 11b and 12b as shown in the form of the device in Figures 5 and 6 may also be provided in the forms shown in Figures 2, 3 and 4 if desired.

Referring now to Figures 7 to 10 inclusive which show a form of the device consisting of two separable cooperating members 30 and 31 formed from blanks as shown in Figures 9 and 10, respectively, the member 30 being formed from the blank shown in Figure 9, over a suitable die which

forms a body portion 32, which may be upset between the lines 32a and 32b to form the annular crowned portion 32c as shown. The annular portion inside of line 32b is bent to form the inwardly projecting circular flange 33. The portions 34, 35 and 36 are bent along the lines 34a, 35a and 32a to form the side members as shown in Figures 7 and 8.

The member 31 is formed from the blank shown in Figure 10 having the body portion 37 with the 10 annular crowned portion 37c, the inwardly projecting circular flange 38 and side members 39, 40, and 41 formed in the same manner as described above. A projecting portion on side member 39 is bent along line 42a to form an 15 abutment adjacent to the outlet, and affording the guide and applicator blade 42 and is provided with a serrated cutting edge 43 at the outer end.

When these members 30 and 31 are placed together to form the device as shown in Figures 7 and 8 the side members 39, 40 and 41 of members 31 fit inside of side members 34, 35 and 36 of member 30 respectively and form apertures 48 on either side of members 36 and 41. The inherent resiliency of these members sets up a frictional contact between the side portions thereby holding the two members together. The inwardly directed flanges 33 and 38 are thus oppositely disposed to each other and form a 30 spindle for the core 44 of a roll, 45, of adhesive tape or other ribbon-like material. The core 44 is conveniently of cardboard and of a length such as to contact with the flanges 33 and 38 and be freely revolvable about them.

The co-operating members 30 and 31 are so constructed that the sides 35 and 40 are shorter than sides 34 and 39 and thus when struck up into angular relationship with the members 30 and 31 a slot 46 is afforded adjacent to the apex 40 47 of the container.

The tape when unrolled is dispensed through the slot 46 along the guide 42 and may be severed at any desired point by the serrated edge 43.

It will be observed that when the members 30 and 31 are properly assembled the guide 42 forms a continuation of the plane of the outer surface of the side 35. Thus if desired this guide may be used as an applicator for applying pressure sensitive adhesive tape directly onto a surface as desired, thus eliminating extra handling, and at the same time leaving one of the user's hands free to hold two or more objects in desired position for receiving the tape.

Having thus described my invention and illustrated its use, what I claim as new and desire to secure by Letters Patent is:

1. In a roll-holding and dispensing device for adhesive tape, a pair of coaxial disc-like side portions, a bridge portion connecting said disc-like side portions and a severing blade on said bridge portion said blade having an applicator portion extending in a plane substantially tangential to the perimeter of one of said sides whereby the tape may be pressed down on a surface as dispensed.

2. In a roll-holding and dispensing device, a pair of nested members having converging side walls affording an outlet, and members including means for axially supporting a roll of tape adapted to be supplied through said outlet.

3. In a roll-holding and dispensing device, a pair of nested members having converging side walls affording an outlet, and members including means for axially supporting a roll of tape

adapted to be supplied through said outlet and a severing blade adjacent to said outlet.

4. In a roll-holding and dispensing device, a pair of nested members having converging side walls affording an outlet, and members including means for axially supporting a roll of tape adapted to be supplied through said outlet, one of said converging portions being extended to form a severing blade.

10 5. In a device for dispensing tape, a pair of nested separable members each having peripheral walls extended to form two converging portions spaced to afford an outlet, means on one of said members for supporting a roll of tape to be dispensed through said outlet, and one of said converging portions being provided with a severing blade extending as a continuation of the plane of the outer surface of the other converging portion.

20 6. In a device of the character described, a container formed of two separable blanks provided with peripheral wall portions interrupted to afford openings in the container, said peripheral walls being extended to form converging portions the ends of which are spaced to afford an outlet, and means for holding a roll of sheet material in said container for dispensing therefrom through said outlet.

25 7. In a device of the character described, a container formed of two separable nested members, each to be shaped from a blank of material to produce peripheral side walls whose adjacent ends are extended tangentially with respect to the body portions to form converging walls terminating in an outlet, one of said converging walls

being extended and bent at substantially a right angle to form a severing blade.

8. In a device of the character described, a container for adhesive tape formed of two separable nested members, each to be shaped from a blank 5 of material to produce peripheral side walls whose adjacent ends are extended tangentially with respect to the body portions to form converging walls terminating in an outlet, one of said converging walls being extended and bent at substantially a right angle to form a severing blade, 10 said body portions being provided with inwardly directed axial annular flanges for engagement with a roll of adhesive tape to be dispensed through said outlet.

15 9. In a holding and dispensing device for a roll of adhesive tape, a pair of co-axial disc-like side portions, means attached to said side portions for supporting same in spaced parallel relation, said latter means being provided with an extended 20 portion forming a severing blade and a portion of said severing blade extending in a plane substantially tangential to the perimeter of said side portions to form means for applying the tape as dispensed prior to severing of the dispensed 25 portion.

10. In a roll holding and dispensing device for adhesive tape, a pair of coaxial disc-like side portions, a bridge portion connecting said side portions, and a severing blade on said bridge portion, 30 said severing blade being extended from said bridge portion to form an applicator whereby the tape as dispensed may be simultaneously applied to a surface.

GEORGE H. HALPIN. 35
